UNITED STATES PATENT OFFICE.

CLARENCE LADD-DAVIS, OF BROOKLYN, NEW YORK, ASSIGNOR TO HIMSELF, AND
JAMES A. TAYLOR, JOINT TRUSTEES, OF BROOKLYN, NEW YORK.

AUTOMATIC FIRE EXTINGUISHER.

Refiling of application Serial No. 756,637, filed March 25, 1913. This application filed July 28, 1919.
Serial No. 313,926.

To all whom it may concern:

Be it known that I, CLARENCE LADD-DAVIS, a citizen of the United States, residing at the borough of Brooklyn, in the county of 5 Kings, city and State of New York, have invented certain new and useful Improvements in Automatic Fire Extinguishers, of which the following is a specification.

The main object of my invention, in its 10 broad scope, is to provide an automatic fire-extinguishing apparatus, by the use of which any suitable fire extinguishing material of any fluent fluidal form and consequently capable of flowage, such as fine granular 15 powder, water, chemical solutions, or gas, or a combination of any two or more thereof, upon the surrounding temperature reaching an abnormally high point, will be automatically projected from the receptacle of the 20 apparatus in practically all surrounding dimensions of space; each of which devices will be individually complete within itself, and not dependent upon any exterior mechanism for actuation; which may be shifted 25 into a new position by any ordinary mechanic; which may be easily refilled and replaced after actuation many times; and which will not deteriorate thru age, etc.

The particular form of embodiment of 30 my invention set forth herein, is one form thereof more particularly designed and adapted for use in distributing fire extinguishing material of the dry powder form; but, with little if any modification of the 35 construction shown, and without departing from the scope of my invention, the same may be made capable of use with any other form of fluent fluidal fire extinguishing material.

In the preferred form in which I have 40 found my broad invention to be best applicable to bring about the most perfect distribution of the fire extinguishing fluent fluidal material thruout the adjacent fire 45 zone, the receptacle is revolvably mounted in a gyroscopic frame, which is pendulously supported by a chain or other flexible support to a ceiling ring or hook, in such manner that such support will be torsionally 50 twisted upon rotation of such frame, and will be again untwisted by the action of gravity when the torsion has reached its limit. For this purpose I have found a double chain (as shown in the drawings)

particularly applicable and desirable. In 55 this form of the device the rotation is given to the receptacle by a motor-spring contained or carried by the receptacle, and normally locked by a suitable thermo-trip; and the action of this spring when released, rotates 60 the receptacle within the gyroscopic frame, and also vibrates such frame so as to twist the double or unswiveled chain or flexible support, and this combination of forces, coupled with the vibration of the frame 65 gives a gyratory, pendulous and rising and falling motion to the entire device which it is impossible to describe in special terms, but which results in distributing the fluid 70 in the receptacle equably thruout practically all dimensions of space, both above and below, and in the immediate vicinity of the point of suspension.

My said invention is fully shown and described in the following specification, of 75 which the accompanying drawings form a part, wherein similar letters or numerals of reference designate like or equivalent parts wherever found thruout the several views, and in which—

Figure 1 is a side view partially in central longitudinal section, of the main portion of one form of my improved automatic fire extinguisher, designed for distributing a fire extinguishing powder upon the adjacent fire 85 zone.

Figure 2 is a top view thereof, taken, in section on the line *a—a* of Figure 1.

Figure 3 is a top plan view of same showing in dotted lines the position assumed by 90 certain of the parts upon the automatic action when the temperature reaches the predetermined abnormally high point, the standards of the supporting swinging gyroscopic frame alone being shown in section; 95 what is the right of Fig. 1, being therein shown as the left side.

Figure 4, is a top plan view in detail of the motor-spring rewinding ratchet-plate and release mechanism, taken on the line 100 *b—b* of Figure 1.

Figure 5 is a side view in detail looking toward the left of Figure 1, of the mechanism shown in Figure 4, showing in full lines the locking, and in dotted lines the releasing, positions thereof.

Figures 6 and 7 are views in detail, but on slightly different scales, each partially in

section, of my improved fusible-solder thermo-trip, which I prefer to use as the automatic thermo-release in my said improved automatic fire-extinguisher.

5 Figure 8 is a side view of a portion of the lift-ratchet and its actuating lever, the movement of which lifts the spider so as to uncover the outlet orifices of the receptacle; and Figure 9 is a view of the entire device 10 as it appears when in position and ready to be automatically set into operation when the temperature reaches the predetermined abnormally high point.

15 Referring to the drawings:—

15 The reference letter A designates a frame, of any suitable shape or contour, usually of the rectangular form shown, made of any suitable material, but usually of cast metal, iron, steel, bronze, etc., and for convenience 20 of description such frame will be herein-after referred to herein as the "gyroscopic-frame". Within such frame is revolvably supported the receptacle B, usually formed of any suitable sheet metal, and usually but not 25 necessarily of the cylindrical form shown, the bottom plate 1 thereof being centrally swaged upward and inward at the center as shown at 2, to form the motor-spring cavity 3', and also provided at the periphery 30 with the annular groove 4, into which fits the lower edge of the annular closure-ring 5; the joint at such groove, and also that between the top of such ring and the peripheral wall 7 of the receptacle being usually 35 made air tight by seals 6 and 8, of any suitable easily frangible material.

40 The annular wall 7 of the receptacle is usually of any suitable sheet metal, and within the same and formed of similar material is usually and preferably located a deflecting annular wall 9 of the truncated cone form shown, with the base adjacent to the bottom plate 1, which wall is swaged outward and then inward at a plurality of 45 points so as to form securing brackets 10, by which such deflecting wall is secured to the outer wall 7, and bottom-plate 1, usually by suitable rivets, as clearly shown in Fig. 1.

50 In any event, and especially in the devices used for the distribution of a fire extinguishing fluidal material in the form of a dry powder, an outlet orifice 11, usually in the form of an annular slit broken only 55 by the brackets 10, is left between the lower edge of the annular receptacle wall 7, and the bottom-plate 1, of sufficient width to permit of such material being thrown violently outward freely therethru by centrifugal force when the receptacle is rapidly rotated, which slit is usually of about one-half ($\frac{1}{2}$) an inch in width, but where liquids are to be used, one or more circular orifices, or any shaped orifice more suitable 60 for delivering liquids of watery aque-

ous like character, are used in preference to orifices of the slit form shown; and I do not intend to limit myself to any particular form of such peripherally located centrifugal outlet delivery orifice or to any particular number thereof.

65 In the dry powder form of device shown herein, the top-plate 12 of the receptacle is usually secured to the annular peripheral wall 7, by a folded lock-joint 13, which is also usually and preferably made air tight by soldering. Such top plate is provided, as shown in Figs. 1 and 3, with a plurality of openings 14, (shown in dotted lines in Fig. 3) usually four in number, each of 70 which is provided with a cover-plate 15, hinged to the top-plate 12, by hinges 16; and such cover-plates 15 are provided with downwardly depending side portions 17, so that when such cover-plates are raised at 75 the forward unhinged ends so as to be pivotally thrown upward upon their rear hinges 16, such cover-plates taken all together will form a four-winged or bladed force-fan, the wings or blades of which are 80 each provided at the outer end with depending flanges or end portions projecting in the direction of the draft; which fan so formed upon the rotation of the receptacle will cause a blast of air to be directed 85 down into the receptacle; and until the level of the fluent material, at least at the peripheral edge of the same is below the upper edge of the outlet delivery orifice or slit at the bottom of the inner wall 9, this blast 90 will be wholly forced down thru the annular space between the outer wall 7, of the receptacle, and the inner deflecting wall 9, and out thru the delivery slit 11; after 95 which a portion will pass down within the wall 9, and both streams be directed out thru slit 11; such blast thus greatly assisting 100 in the far and free distribution of the fire-extinguishing material whether of powder, or any other suitable fluent fluidal form. And such combined fan-blades and cover-plates 15, are each provided with the lift-clips 18, formed integral therewith or secured thereto extending over the radial 105 arms 19, of the lift-spider C, the lift-arms 110 20, of which are secured at the lower end to the closure-ring 5, usually by being screwed or riveted to brackets 21, formed integral with or secured to such ring.

115 The top-plate 12 is usually spun or struck up from thin sheet metal and is provided at the center with the cylindrical annular lift-ratchet cavity 22, upon the inner annular wall 23 of which reciprocates easily up and down the central ratchet portion 24 of the lift-spider C, raised by the lift-ratchet 25, upon the movement of the lift or trip-lever 26, (Figs. 1, 3 and 8) upon the rotation of the receptacle as hereinabove described. The joint between this wall 23 and the central 120

pivot-standard 30 is usually made air tight by soldering, or in any other suitable manner.

As shown in Figs. 1 and 2, the receptacle 5 B is secured to the bottom supporting spider D in any desired manner, usually by rivets 27 passing thru the bottom-plate 1 of the receptacle as shown. Such spider D is usually formed in one piece of cast or drop forged 10 metal, iron, steel, brass, etc., having the central cone-shaped portion 29, from the center of which extends upward the central shaft 30, formed integral with such portion 29, in which shaft 30 at either end are formed 15 the cylindrical journal cavities or sockets 33 and 34 which are each provided with suitable anti-friction bushings 35, preferably of plumbago composition, etc., of any desired form.

20 Within the motor-spring cavity or chamber formed by the cone shaped strip portion of such spider D, is located the flat steel coil motor-spring E, the outer end of which has a perforation to receive the securing-lug 36, secured to or formed integral with one of the 25 standards of 29; and the inner and central end of such motor-spring is provided with a like securing perforation by which the same may be secured to the motor-spring 30 shaft F, by being slipped over the headed securing screw 36', firmly screwed into such shaft. Such motor-spring shaft F is provided 35 at the top or inner end with the pointed pivot pin 37, fitting into the bottom journal bearing cavity 34, of the spider standard 30, and at the bottom with a journal cavity 38, similar to 34, and bushed in the same manner, adapted to receive the bottom pivot-pin 52 secured in the frame A by 40 a drive-pin or screw 53, and formed integral with the secondary-cable support ring 71. Such motor spring shaft F is also provided at the outer and lower end with a suitable square or nut portion 39, (Figs. 1 and 4), 45 upon which is tightly sweated the ratchet-plate 40, (shown in detail in Fig. 4), so that the two will simultaneously rotate, which plate 40 is provided with the ratchet lock-slots 41, the safety securing bolt slot 43, and 50 at the outer end of the side extension 42 thereof, with the side trip-lever securing slot 44.

In assembling, the inner end of the motor-spring E is slipped over the screw 36' on the motor-spring shaft F, and such spring and shaft slipped up into the motor-spring cavity into the position shown in Fig. 1, the ratchet-plate 40, having been of course sweated on to the motor-shaft, and the anti-friction sleeve placed in position in the cavity 38, and the outer end of the motor-spring is then slipped over the securing stud 36, and the ratchet-plate 40 secured against 60 rotation by the insertion into position of the securing safety thumb-screw 45, having

the thumb-piece 46, into spider D, after which the binding wires or clamps holding the spring under tension are removed, and the combined spring securing and dust-plate 28, which is usually in two parts, the split 70 thereof not being shown, is secured in place so as to form a dust-proof bottom for the motor-spring cavity, usually by means of screws 28', as shown in Fig. 1. Usually an anti-friction washer of soft material impregnated with plumbago, etc., shown at 47, is interposed between the dust-plate 28 and the ratchet-plate 40, to minimize the friction, and at the same time close the central orifice thru which the shaft F passes against 80 the entrance of dust.

After the motor-spring is in position, the annular closure-ring 5, is next slipped down into position so as to close the outlet orifice or slit 11, of the receptacle B, and such receptacle filled with the required fire-extinguishing fluent fluidal material thru one or more of the air inlet orifices 14. The combined cover and fan-plates 15 are then forced down into the closing position shown 90 in Fig. 1, and the joints thereof with the top-plate, as well as the joints of the closure-ring 5, with the bottom plate 1, and receptacle-wall 7, for the purpose of preventing deterioration of the fluidal fire-extinguishing material thru admission of air, vapors or gases to the interior thru such joint, are all sealed air-tight with a material which will quickly give way so as to allow the joint to easily open when required, such as sealing-wax, 100 paraffin, etc., or even by the same fusible solder used in the thermo-trip, which melts at 155 F.

The lift-ratchet 25 is then slipped into position in the ratchet-cavity 22 and the lift spider ratchet 24, (Figs. 1 and 8), slipped down over the same, and by a slight turning movement of both lift-ratchet 25, and lift-spider C contra clockwise toward the left in Fig. 3, on the receptacle B, the top radial 105 arms 19 of such spider are swung under the lift-fingers or lugs 18, of the cover fan-plates 15, formed integral with or secured to such plates, in such manner that the lifting up of the lift-spider C by the action of the radial arms on such fingers or lugs will force such cover fan-plates into the raised and open position, so as to uncover the air-inlet orifices 14; and after the spider C is thus placed in position the same is secured 110 firmly to the closure-ring 5, by suitable screws 21, passing thru brackets formed integral with and extending upward from closure-ring 5, and screwing into the lift-bars 20, which are but downwardly depending 115 integral extensions of the radial arms 19, of the lift-spider C.

The throw or trip-lever 26 of the lift-ratchet 25, is of spring-steel, and extends 120 from the lift-ratchet, (to which it is firmly

secured, usually by a screw or screws as shown in Fig. 8), out from under the central boss portion of the lift-spider C, which forms a cover-plate for the annular lift-ratchet cavity 22, thru a throw orifice or slot 49, (Fig. 1,) of about the length of one fourth of the periphery of such cavity and boss; and such spring throw or trip-lever 26, is normally held in the raised and tripping position shown in full lines in Fig. 1, by a segmental trip-rail 50, formed integral with or firmly secured to the top-plate 12, of the receptacle A, usually extending down into the lift-ratchet cavity 22, when formed of a separate piece, but in any event extending above the top-surface of the top-plate 12, and being of slightly less length than the throw orifice or slot 49, in such manner that as such trip-lever is forced off from such trip-rail upon the initial rotation of the receptacle, the same will by its own resiliency be forced down into the position shown in dotted lines in Fig. 1, so as to thereafter permit of free rotation of the receptacle, for the reason that in such depressed position the outer end 90 thereof will no longer contact with the trip-lug 91, of the gyroscopic-frame A. The position of all the parts as shown in full lines in Fig. 3, are those such parts are in, when the device is suspended ready for operation, as shown in Fig. 9.

The receptacle B having been filled and sealed as hereinbefore described, the same is slipped into the gyroscopic-frame A, and the pivot-pins 51 and 52 placed in position in the central bosses of the frame and secured therein by drive-pins 53, so as to pivotally and revolutely mount the receptacle within the frame (anti-friction washers of plumbago composition, etc., 55, being usually placed in the positions shown in Fig. 1, between the frame and receptacle to lessen the friction) and the thermo-trip G is then secured to the frame A, by means of the screws 57, passing thru the frame A and screwing into the main-plate 60, of such thermo-trip, as shown in Figs. 6 and 7, and the safety cotter-pin 58, passed thru suitable registering holes in the top end portion 65 (Figs. 1, 6 and 7) of the trip-lever 63 of such thermo-trip, G, and thru the downwardly depending fin 66 of the supporting spider D, so as to prevent release and rotation of the receptacle during transportation of the device.

As shown in position in Figs. 1 and 9, and in detail in Figs. 6 and 7, the thermo-trip G, in the form of my invention which I prefer to use, comprises a brass securing or main-plate 60, (adapted to be firmly but removably secured to the gyroscopic-frame A, by suitable screws 57) which is provided with the rock-lug 61, having the knife-edge 62, against which normally rests and on which when actuated rocks the thermo-trip release-

lever 63, (located in a slot open to what is the left of Fig. 1 as hereinafter described) which is secured to the main-plate 60 by a film 64, of easily fusible solder, usually of the well known composition used in automatic fire extinguishing devices which fuses at approximately 155 F. Such thermo-trip may be of any suitable desired form, but that shown I have found efficient for the purposes desired; and in the drawings Fig. 1 shows the trip in position on the gyroscopic-frame; a portion of which frame, as well as part of the trip-mechanism are broken away in order to more perfectly show the construction. Figs. 6 and 7 are views partially in section respectively vertical and horizontal looking from the left and from the top of Fig. 1, save only that in Fig. 7, I have not deemed it necessary to show the trip-cable 70 attached thereto, for the reason that I have shown such trip-cable attached in one manner in Fig. 1, and in a slightly modified form of attachment in Fig. 6, and have also shown therein the rock-lug 61, at the end of which is integrally formed the lug 68, between which and the main-plate 60 is left a slot to receive the shank of the trip-lever 63.

To the lower end of the thermo-trip release lever 66, is firmly secured (Figs. 1, 6 and 9), usually by soldering the same thereto as indicated at 69, the end of the secondary supporting trip-cable 70, which is preferably formed into a loop 70' adjacent thereto, and has the bight of such loop secured either to the lower end of the trip-lever 63, by low-fusible thermo-release solder, as indicated at 69' of Fig. 1 or to the main-plate 60, in the modified form of construction shown in Fig. 6; and from the solder-loop connection so made the trip-cable passes thru the supporting-ring 71, to the secondary hanger-ring or support 73, (Fig. 9) supporting the extinguisher by the contact of the weight 85 secured to the end of trip-cable 70, with the outer right hand face of the hanger-ring 73; whereby upon the thermal release, of the trip-lever 63, and the pendulous vibration by gravity of the extinguisher (as shown in dotted lines) such trip-lever 63, passing freely thru the ring 71, such trip-lever 63, and the supporting trip-cable 70, will be drawn back by the gravity of the weight 85, thru the hanger-ring 73, until the stop 86, rigidly secured to such cable, will leave the cable 70, carrying the trip-lever 63, at one end, and the weight 85, at the other, suspended by the center by the ring 73, fully out of interfering contact with the device during its operative movements, all as clearly shown in dotted lines in said Fig. 9.

The receptacle, thermo-trip, etc., having all been placed in position in the gyroscopic-frame A, as hereinbefore described, the curved rear end portion or supporting lug 74, of the ratchet-plate lock-bar 75, (Figs. 4

and 5), is passed thru the perforation 76, in the gyroscopic-frame A, and on and over the end of the spring 77, (Figs. 1 and 4) secured by a screw 79 to a lug 78 formed integral with or secured to the frame A; and such spring 77, normally tends to force such lock-bar 75, down into the position shown in dotted lines in Fig. 5, so as not to interfere with the free rotation in the frame A of the receptacle B, and the like rotation of the ratchet-plate 40. Such lock-bar 75 is then lifted up into the position shown in full lines in Fig. 5, and the end piece or extension 42 of the ratchet-plate 40, swung against the tension of the spring E and then dropped back into the slot 80 of such lock-bar 75. In order to permit of free movement in both directions relative to the lock-bar 75, of this end piece or extension 42 of the ratchet-plate 40, the same is preferably slightly twisted so as to have normally the slanting position shown in Fig. 5; and the lock-bar 75, is so loosely fitted by its supporting-lug 74, in the perforation 76, in the gyroscopic-frame A, that the outer free end carrying the slot 80, will move freely in all directions, up, down, and sideways, with a universal loose rocking motion at the joint formed by 74, and 76, so that it will accommodate itself to the outward movement from the slot 80, of the end-piece 42, of the ratchet-plate 40, upon the operation of the apparatus, as hereinafter more particularly described, in such manner as to release 42 from the slot 80, and permit such lock-bar 75, to drop down into the position shown in dotted lines in Fig. 5; where it will no longer prevent rotation of the ratchet-plate 40, in either direction.

The parts being in the position shown in Figs. 4 and 5, the safety cotter-pin 81, (Figs. 1 and 4) is passed thru the perforations formed to receive it in the lock-bar 75 and the downwardly extending end flange 82 at the end of the extension 42 of the ratchet-plate 40; after which the safety thumb-screw 46 is usually removed, and the device, locked against accidental release by the safety cotter-pins 58 and 81, will be ready for shipment.

When in position ready for use, the device is supported from a point which when the same is in operation will be the top thereof, by any suitable means which will permit of gravitational pendulous movement of the gyroscopic-frame; such supporting means being usually flexible and unswiveled, and I have found in actual practice a double chain 84, passing thru the ring 51' of the top pivot pin 51, and secured to a ceiling ring or support 83, (Fig. 9), highly efficient for such purpose. For I have found by actual experiment, and operation that when released, by the consequent rotative constant movement of the receptacle within the gy-

roscopic-frame, while at the same time such gyroscopic-frame is performing pendulous swinging movements, the unswiveled double chain support 84, will be twisted upon itself first in one direction, and then in the other; and that the combination of all the various motions of the whole and the several differentially moving parts of the device, will be practically indescribable, in plain terms, by reason of their extreme swiftness. But I have found that the twisting and untwisting of the unswiveled chain, gives rise to a rising and falling of the gyroscopic-frame, and also to what may be best termed an exaggerated nutation, or nutative movement, of the gyroscopic-frame, and the receptacle retained and rotating in such frame; which will cause the axis of rotation of the receptacle to successively assume almost an infinite number of positions; which consequently causes the fluidal fire-extinguishing material, to be violently centrifugally discharged, in practically an infinite number of special planes, up, down, horizontally and diagonally to the horizontal and vertical; whereby such fire-extinguishing fluidal material, if the room be a small one, say eight or ten feet square, will be thrown violently against the ceiling, floor, and four walls, in an astonishingly equable and even distribution, thus being brought into contact with the adjacent fire-zone, irrespective of its spacial dimensional location relative to the ceiling ring or support 83.

The device is also further supported in position to be gravitationally vibrated upon the main support when thermally released by the secondary supporting trip-cable 70 secured at its lower end to the trip-lever 63, of the thermo-trip G, which passes thence thru the lower or pivot-pin ring 71, (Figs. 1 and 9), to and thru a supporting ring or ceiling support 73, (Fig. 9), and is provided at the outer and free end with a weight 85, and has secured thereto between the ring 71, and support 73, a stop disk 86, too large to pass thru the support 73, so as to hold the cable suspended out of the way of the moving device, and in the position shown in dotted lines in Fig. 9, when thermally released.

After the device has been suspended from the ceiling supporting hooks or eyes 83 and 73, (Fig. 9), in the manner described, the safety cotter-pins 58 and 81, are removed, and thereafter the device is ready for automatic-thermal actuation upon the surrounding temperature reaching the proper high point at which the thermal solder joints 64 and 69' will fuse. When this temperature is reached, the smaller supporting fuse 69' (for the reason that it supports a large portion of the weight of the device) will part first, and the device falling by gravity the length of the bight or loop 70', this will cause such a sudden strain to be brought upon the lower

end of the release-trip-lever 63 (the thermal solder joint 64 of which has also melted), as to rock the same upon the knife-edge 62, of the rock-lug 61, of the main-plate 60, of the thermo-trip G, and throw such trip-lever completely out of the slot of such main-plate, whereupon such trip lever upon the continued downward swing of the device will be drawn out thru the ring 71, and into the position shown in dotted lines in Fig. 9, by the action of the weight 85 secured to the other end of the secondary supporting trip-cable 70. The instant the release trip-lever 63 releases the stop-lug 65 of the supporting bottom spider D, the force of the motor-spring E exerted upon such spider thru the securing lug 36, sets the receptacle into rotation upon the pivot-pins or pintles 37 and 51, within the gyroscopic-frame A. The motor-spring E is of such power that when the receptacle has all but completed one complete revolution, and the trip-end 90 of the trip-lever 26 of the lift-ratchet 25, comes in contact with the side of the downwardly and inwardly projecting trip-lug 91, (as shown in Fig. 1, at upper right-hand corner, in full lines with contacting end of lever 26, in dotted-lines; and also shown in dotted lines at upper left-hand corner of Fig. 3) which trip-lug 91, is formed integral with the side or upright member of the gyroscopic frame A; and against the opposite side of which trip-lug, such trip-lever 26, was in close abutment (as shown at the left side of Fig. 3) up to the moment of the thermal release, and the consequent rotation of the receptacle by the action of the motor-spring E.

And while such trip-lever 26 will thus be momentarily stopped against further rotation upon contacting with 91, the receptacle will continue to rotate. The stopping of the trip-lever 26 will also cause a slight relative stopping of the lift-spider C, whereby the closure-ring 5, will be given a slight rotative movement upon the receptacle sufficient to break the frangible seals at the top and bottom of the closure-ring 5. Such relative rotative movement is very short, say from $\frac{1}{6}$ th to $\frac{1}{4}$ th of an inch at the utmost; and is limited by the stop-pin 92, rigidly secured at its lower end to the covering top-plate 12, of the receptacle B; which stop-pin is of such length as to be always located in the stop-slot 93, formed in and thru the central hub portion of the lift-spider C, even when such lift-spider is in the fully raised and outlet opening position. Inasmuch as in the construction shown in the drawing the expulsive rotative movement of the receptacle B, with in the gyroscopic-frame A, is contra clock-wise toward the left (indicated by the arrow γ , in Fig. 3) the seal-breaking relative rotative movement of the spider C per contra, is clock-wise toward the right, as indicated by the arrow α , in such Fig. 3. Before the

thermal release of the device, and when in the position shown in Figs. 3 and 9, the stop-pin 92, is located at the extreme left-hand end of the slot 93, and when the relative rotative movement of the spider C, on the receptacle B, is brought about in the manner just described, the stop-pin 92, by its abutment against the right-hand end of the stop-slot 93, of the spider C, will instantly cause the spider to come to rest relative to the receptacle, by again taking up the rotative movement of the receptacle, while the trip-lever 26, still being in the raised position and stopped by the trip-lug 91, will still remain stationary, holding stationary with it the lift-ratchet 25, secured to its inner end;

And thereupon the continued rotative movement of the lift-spider C, with the receptacle, will cause the lift-ratchet 24, of the spider to ride up on the ratchet 25, which is rigidly secured to or formed integral with the lift-spider C, so as to lift such spider, and consequently the closure ring 5, so as to open and uncover the annular outlet orifice or slot 11; and as soon as the coacting flat surfaces of the teeth of the two ratchet-wheels 24 and 25, indicated in Fig. 8, at 24' and 25', have slid upon each other so as to hold the lift-spider C in the raised position, the resilient spring trip-lever 26, will pass off from the segmental trip-rail 50, as shown in dotted lines in Fig. 3, and will be forced by its own resiliency down into the position shown in dotted lines in Fig. 1, so as to clear the stop-lug 91 formed integral with the gyroscopic-frame A, after which such trip-lever 26 will of course be free to rotate with the receptacle.

With a motor-spring of the ordinary coil clock-spring form shown, made of suitable spring steel, and of say about 18 feet in length, about one thirty-second of an inch in thickness, and about one and one quarter inches in width, wound into a close coil of about three and one-half inches in diameter, contained in a motor-spring cavity of about six or so inches in diameter, and with a receptacle weighing when filled from thirty-five to forty pounds, I have found that the spring at just the instant of the contacting of the lever 26 with the stop-lug 91, will have an inertial force of approximately somewhat over forty pounds; and that by the time such spring has reached the limit of its unwinding, the receptacle will be rotating at a high rate of speed, estimated by experts to be at between 800 and 1000 revolutions per minute, and such revolution will not cease for about eight or so minutes, altho the receptacle will have been fully emptied of its contents by the centrifugal force, in less than two minutes. This distribution of the fire-extinguishing fluent fluidal material is greatly assisted by the action of the deflecting vanes 95, and also

by the blast of air driven down thru the annular space 96, between the outer wall 7, and the inner conical deflecting wall 9, of the receptacle, and out thru the annular outlet orifice or slit 11, by the fan-like action of the cover fan-blades 15, which have been lifted into the open position so as to uncover the air-inlet orifices 14, by the lifting action of the radial arms 20 of the lift-spider 'C, exerted upon the lift-clips or lugs 18 of such cover-plates or fan-blades 15, as such spider C is forced upward by the action of the lift-ratchet 25, as hereinbefore described.

When the motor-spring E has fully unwound, the continued rotation of the receptacle automatically withdraws the lug 36 therefrom, whereupon the outer inwardly curved end 98 of such motor-spring is by the natural resiliency thereof forced back toward the center and into the position shown in dotted lines in Fig. 2; and immediately upon such release some rotative motion being communicated to the motor-spring shaft F, by the minimized slight friction exerted upon the pivot-pin 37 by the swiftly rotating receptacle, such motor-spring shaft will begin to rotate in the same direction as the receptacle upon the bottom pivot-pin 52, carrying with it the ratchet-plate 40, the end-piece or extension 42 of which is immediately thrown out of the securing-slot in the end of the ratchet-plate lock-bar 75, and into the releasing position shown in dotted lines in Fig. 5; and the instant that such lock-bar 75 is thus released from contact with the extension of the ratchet-plate, the spring 77, will force such lock-bar down into the position shown in dotted lines in Fig. 5, so that such lock-bar will be wholly below the upper edge of the bottom-bar of the gyroscope frame A, so that thereafter the ratchet-plate 40 will be free to rotate in such frame without coming in contact with such lock-bar 75.

The receptacle having been thus emptied, in order to render the same ready for use without return to the factory, the same is taken down from the support 83, and the screws 21 securing the lift-spider C to the closure-ring 5 removed, and the spider lifted off, and the ring 5 pushed down into the closing position shown in Fig. 1, and hermetically sealed by soldering as hereinbefore described. The receptacle is then refilled by way of the orifices 14, and the lift-spider replaced and secured to the closure-ring 5 by the screws 21; the trip-lever 26 having first been of course swung back and over the segmental trip-rail 50, and into the position shown in full lines in Fig. 3, and after the receptacle is filled the joints between the receptacle top-plate 12, and the cover fan-plates 15 are sealed as hereinbefore described. Such filling may of course best be done by first removing the receptacle from

the gyroscopic-frame, by the removal of the pivot-pins or pintles 51 and 52, but this is not essential; and when the receptacle is so removed, the dust-plate 28 is taken off, the outer end of the motor-spring E is slipped over the securing-lug 36, and the motor-spring rewound by rotation of the ratchet-plate 40 (usually by the use of a suitable spanner, not shown) after which such ratchet-plate is locked in position by the insertion of the safety thumb-screw-bolt 45 thru the slot 43 of such ratchet-plate 40, and the screwing of the same into the spider D, as shown in Fig. 1.

When the receptacle is not removed from the gyroscopic-frame A for such filling and rewinding, the operation is slightly different, being as follows:—The dust-plate having been removed, the outer end of the spring E is secured to the lug 36, and the dust-plate having been replaced, and either the old thermo-trip resoldered, or a new one, secured in position, the safety cotter-pin 58 is then passed thru the trip-lever 63, and the fin 66 of the bottom-spider D, so as to lock the receptacle against rotation in the gyroscopic-frame.

The various parts having been thus assembled and in operative position, the removable pawl-plate 100, provided with the spring-pawl 101 which is adapted to coact with the pawl-slots 41 of the ratchet-plate 40, to prevent retroactive rotation of such ratchet-plate by the action of the motor-spring E, while the same is being wound up, is placed in position on the bottom-bar of the gyroscopic-frame A, and secured in place by a pin or screw 102. (Fig. 1).

The motor-spring E, may then be wound up, either by pressure exerted upon the extension 42, or by the use of a suitable spanner (not shown) adapted to fit into the pawl-slots 41, of such ratchet-plate 40. The motor-spring E having been fully wound up the end of the ratchet-plate extension 42, is allowed to slip back into the securing-slot 80, of the release lock-bar 75, and the safety cotterpin 81, and safety thumb-screw bolt 45, having been placed in position, the removable pawl-plate 101, (which is only in position on the frame A during such rewinding) is removed; and the device having been again suspended in position by the cables 84 and 70, (Fig. 9) and the safety cotter-pins 58 and 81, having been removed, the device will be again ready for automatic action upon the surrounding temperature reaching the proper abnormally high point; all as hereinbefore described.

It is self evident that the shape and position of the outlet or outlets thru which the fire-extinguishing fluidal material is expelled, may be widely varied, and may be of any desired number, this all according to the surrounding conditions, and the particular

kind of such material used; and the same applies also to the air-inlet or inlets; and consequently I do not intend to limit myself to the exact form of construction shown, relative to this or any other parts of said device; and wherever I have in the claims hereof used the singular number, I intend to cover and include thereby the plural wherever the same may be found applicable.

10 I claim:—

1. In a device of the class described, a receptacle adapted to contain a fire-extinguishing fluent fluidal material; and mechanical power-means for simultaneously giving a plurality of material expelling motions to the receptacle.

2. In a device of the class described, a receptacle adapted to contain a fire-extinguishing fluent fluidal material; and mechanical positive power-means for simultaneously giving a plurality of material expelling motions to the receptacle, some of which are oscillatory vibratory, and others rotative in different planes.

25 3. In a device of the class described, a normally closed hermetically sealed receptacle for containing a fluent fluidal fire-extinguishing material; and positive power-means for causing synchronous successive, vibratory and also rotary, material expelling and distributing movement and motion of the receptacle, when thermally released.

35 4. In a device of the class described, a receptacle adapted to contain a fluent fluidal fire-extinguishing material; a motor-spring for giving positive centrifugal material expelling rotation to the receptacle, in actuating connection at its working end with the receptacle, in such manner as to be automatically released from such receptacle upon reaching the limit of its throw.

45 5. In a device of the class described, a receptacle adapted to contain a fluent fluidal fire-extinguishing material; a motor-spring for giving positive centrifugal material expelling rotation to the receptacle, in actuating connection at its working end with the receptacle, in such manner as to be automatically released from such receptacle upon reaching the limit of its throw; and a thermo-trip normally locking the receptacle against rotation.

55 6. In a device of the class described, a receptacle for containing a fire-extinguishing fluidal material having an outlet in the peripheral wall thru which such material will be expelled upon rotation of the receptacle; closure means normally closing the outlet; motor-means for putting the receptacle into fluid expelling rotation; a thermo-trip normally locking the receptacle against rotation; and means for moving the outlet closure means into the outlet opening position upon the thermal actuation of the thermo-trip.

7. In a device of the class described, a receptacle adapted to contain a fire extinguishing fluent fluidal material, provided with an outlet thru which the material may be expelled upon proper motion being given to the receptacle; closure means normally closing the outlet; positive power-means for putting the receptacle into material ejecting motion; means for automatically disconnecting such positive power means from the receptacle when such receptacle has made a certain predetermined number of ejecting movements; a thermo-trip normally locking the receptacle against motion; and means for automatically moving the outlet closure means into the open position upon the release of the thermo-trip.

8. In a device of the class described, a gyroscopic frame; means for movably supporting the frame; a receptacle adapted to contain a fire-extinguishing fluidal material and to eject the same when rotated revolvably mounted in the frame; a motor-spring for rotating the receptacle in the frame; and a thermo-trip normally locking the receptacle against rotation.

9. In a device of the class described, a receptacle adapted to contain a fire-extinguishing fluidal material and to eject the same by rotative movement of the receptacle; a support revolvably supporting the receptacle capable of pendulous vibration; positive power means for rotating the receptacle; and a thermo-trip the release of which upon the surrounding temperature reaching a predetermined abnormally high point will cause rotation of the receptacle and vibration of the support.

10. In a device of the class described, a receptacle adapted to contain a fire-extinguishing fluidal material provided with a delivery orifice through which the fluidal material may be expelled upon proper motion being given to the receptacle; means normally closing the delivery-orifice; a thermo-trip; positive power means for putting the receptacle into fluid ejecting motion upon the actuation of the thermo-trip; a normally closed air inlet orifice; and means for opening the outlet and inlet orifices upon the actuation of the thermo-trip.

11. In a device of the class described, a receptacle adapted to contain a fire-extinguishing fluidal material and to peripherally eject the same having an outlet orifice; an air inlet or venting orifice; means normally closing the outlet; and means normally closing the inlet; means for imparting ejecting motion to the receptacle; a thermo-trip normally locking the receptacle against movement; and means for opening the outlet and inlet orifices upon the actuation of the thermo-trip and the consequent putting into motion of the receptacle.

12. In a device of the class described, a

gyroscopic-frame; a receptacle adapted to contain a fire-extinguishing fluidal material revolubly mounted in the gyroscopic-frame; and a flexible support pendulously supporting such gyroscopic-frame.

13. In a device of the class described, a gyroscopic-frame; a receptacle adapted to contain a fire-extinguishing fluidal material revolubly mounted in the gyroscopic-frame; and a flexible support supporting the gyroscopic-frame from above in such manner as to be torsionally twisted upon rotation of the gyroscopic-frame.

14. In a device of the class described, a receptacle adapted to contain a fire-extinguishing fluidal material; a motor for rotating the receptacle; a main support pendulously supporting the receptacle; a thermo-trip; and a secondary support connected with the thermo-trip in such manner that upon the release of such thermo-trip upon the surrounding temperature reaching a predetermined abnormally high point the receptacle will be pendulously vibrated by gravity upon the main-support.

15. In a device of the class described, a receptacle adapted to contain a fire-extinguishing fluidal material having an annular wall in the form of a hollow truncated cone provided with an annular outlet-slit adjacent to the base; closure means normally closing such outlet-slit; motor means for rotating the receptacle; a thermo-trip normally locking the receptacle against rotation; and means for moving the outlet closure into the outlet opening position upon the release of the thermo-trip and the consequent rotation of the receptacle.

16. In a device of the class described, a receptacle adapted to contain a fire-extinguishing fluidal material having an annular peripheral outlet-slit in the wall thereof; a closure-ring normally closing such outlet-slit; means for giving fluid expelling motion to the receptacle; a thermo-trip normally locking the receptacle against motion; and means for automatically moving the closure-ring so as to uncover the outlet-slit upon the release of the thermo-trip and consequent fluid expelling motion of the receptacle.

17. In a device of the class described, a receptacle adapted to contain a fire extinguishing fluidal material having an annular outlet-slit in the peripheral wall thereof; a closure-ring normally closing the outlet-slit; motor means for rotating the receptacle; a thermo-trip normally locking the receptacle against rotation; and means for automatically moving the closure-ring so as to uncover the outlet-slit upon the release of the thermo-trip and the rotation of the receptacle.

18. In a device of the class described, a receptacle adapted to contain a fire-extin-

guishing fluidal material; an outlet orifice in the peripheral wall thereof; a closure-ring normally closing such outlet; a seal of frangible sealing material hermetically sealing the joints between the closure-ring and the boundaries of the outlet; means for causing expulsion of the fire-extinguishing fluidal material upon the actuation of the thermo-trip; and means also actuated upon the actuation of the thermo-trip for first partially rotating the closure-ring so as to break the frangible seal, and for then lifting the same so as to uncover the outlet.

19. In a device of the class described, a receptacle adapted to contain a fire extinguishing fluidal material and to expel the same when rotated; a support revolubly supporting the receptacle, a motor-spring for giving the receptacle rotation; a thermo-trip normally locking the receptacle against rotation; closure means normally closing the outlet of the receptacle; a trip-lever stop; and a trip-lever carried by the receptacle adapted to throw the outlet closure means into the open position upon contacting with the trip-lever stop upon the initial rotation of the receptacle.

20. In a device of the class described, a gyroscopic-frame; a receptacle adapted to contain a fire-extinguishing fluidal material revolubly supported in the gyroscopic-frame and having an outlet orifice; closure means normally closing such outlet; means for giving rotative movement to the receptacle within the gyroscopic-frame; a thermo-trip normally locking the receptacle against rotation; and a spring-lever carried by the receptacle adapted to contact with the gyroscopic-frame upon the initial rotative movement of the receptacle and by the consequent relative movement thereof throw the outlet closure into the open position.

21. In a device of the class described, a support; a receptacle adapted to contain a fluent fluidal fire-extinguishing material, and to expel the same upon rotation of the receptacle, revolubly carried by the support; a motor-spring for giving rotation to the receptacle; a thermo-trip normally locking the receptacle against rotation; and means for automatically releasing the motor-spring from the receptacle, when such motor-spring reaches the limit of its working throw, so as to thereafter permit the free inertial rotation of the receptacle.

22. In a device of the class described, a receptacle adapted to contain a fluent fluidal fire-extinguishing material and eject the same therefrom; a thermo-trip normally locking the receptacle against movement upon a suitable support; and power-means for giving a material expelling motion to the receptacle upon the actuation of the thermo-trip when the temperature reaches a predetermined abnormally high point; the con-

struction and arrangement being such, that upon the actuation of the thermo-trip, the power-means will cause material expelling motion of the receptacle; while at the same time such receptacle will be gravitationally 5 vibratory oscillated; whereby, the combined power and gravitationally caused motions, all of which continue until the material in the receptacle is fully ejected, will bring about the equable distribution of the 10 material in a plurality of planes, and practically all dimensions of space.

23. In a device of the class described, a receptacle adapted to contain a fire-extinguishing fluidal material and eject the same therefrom; a support revolubly and pendulously supporting the receptacle; a motor for rotating the receptacle upon the support; and a thermo-trip normally holding the receptacle 15 in a raised position and locking the same against rotation, the tripping of which upon the surrounding temperature reaching a pre-determined abnormally high point will allow the receptacle to be set into such motion that the fluidal material therein will be ejected into practically all surrounding dimensions of space.

24. In a device of the class described, a receptacle adapted to contain a fluent fluidal fire-extinguishing material which may be ejected therefrom; a thermo-trip normally locking the receptacle in non-material ejecting position; and means for causing a combined, rotary, nutative, oscillatory, gyratory material expelling and distributing motion or motions of the receptacle, upon the thermal actuation of the thermo-trip.

25. In a device of the class described, a support; a receptacle adapted to contain a fluent fluidal fire-extinguishing material revolubly carried by the support; a motor-spring for giving rotation to the receptacle; a central pivot-pin motor-spring shaft forming the central supporting pivot-point of the receptacle; means for securing the inner central end of the motor-spring to such motor-spring shaft; a ratchet-plate secured to the motor-spring shaft for winding up the spring; means for locking the ratchet-plate 40 against retroactive movement, in such manner as to automatically release the ratchet-plate when the motor-spring reaches the limit of its working throw; means normally connecting the outer free working end of the motor-spring, with the receptacle in such manner that such motor-spring free-working end will be automatically disconnected from the receptacle when such motor-spring reaches the limit of its working-throw; and a thermo-trip normally locking the receptacle against rotation; the construction being such, that after the motor-spring reaches the limit of its working throw, and it is automatically disconnected from the receptacle, such receptacle, and also the com-

70 bined ratchet-plate, pivot-pin motor-spring shaft, and motor-spring, will all continue to inertially spin thru the momentum originally derived from the impulse of the motor-spring.

26. In a device of the class described, a receptacle adapted to contain a fire extinguishing fluidal material; a support revolubly supporting the receptacle; means for rotating the receptacle; a thermo-trip normally locking the receptacle against rotation; an outlet in the peripheral wall of the receptacle thru which the fluidal material will be expelled upon the rotation of the receptacle; an air inlet for the admission of air to the receptacle to assist in the expulsion of the fluidal material; a combined fan and cover plate normally closing the air-inlet, adapted when moved into the unclosed position so as to uncover the air inlet to act as a blade fan to deflect the air into the receptacle thru the air inlet; closure means normally closing the outlet; and means, automatically actuated upon the actuation of the thermo-trip, upon the surrounding atmosphere reaching a predetermined abnormally high point, for moving the fan and cover-plate and outlet closure into the open position, so as to open the inlet and outlet orifices.

27. In a device of the class described, a receptacle adapted to contain a fire extinguishing fluidal material having a peripheral outer wall provided with an outlet orifice adjacent to the base of the receptacle; an inner annular wall between which and the outer peripheral wall is an annular free-air-space open at both ends; an upper air inlet orifice; a closure normally closing the air inlet orifice; a closure normally closing the outlet orifice; a support; means revolubly securing the receptacle to the support; means for causing rotation of the receptacle relative to the support; a thermo-trip normally locking the receptacle against rotation; and means for automatically actuating the inlet and outlet closure so as to open the same upon the release of the thermo-trip; and means for causing a current of air to pass down into the receptacle thru the annular space between the two walls thereof, and out thru the outlet orifice, upon the rotation of the receptacle.

28. In a device of the class described, a supporting frame; a receptacle adapted to contain a fire-extinguishing fluidal material, an upper pivot-pin; a motor-spring shaft provided with a pivot-pin coating with the upper pivot-pin so as to form two pivot-journal joints upon which the receptacle may be rotated; a lower pivot-pin secured to the frame upon which the motor-spring is revolubly mounted; a motor-spring secured at one end to the receptacle and at the other to the motor-spring shaft;

means for winding the motor-spring by rotation of the motor-spring shaft; means for locking the motor-spring shaft against reverse rotation; a thermo-trip normally locking the receptacle against rotation by the motor-spring; and means for releasing the motor-spring shaft locking means upon the motor-spring reaching the limit of its unwinding, so as to thereafter permit of the 10 motor-spring and the motor-spring shaft rotating freely with the receptacle upon the lower pivot-pin.

29. In a device of the class described, a receptacle adapted to contain a fire-extinguishing fluidal material having a peripheral wall provided with an outlet orifice adjacent to the base of the receptacle; means for rotating the receptacle; a thermo-trip normally locking the receptacle against rotation; a closure ring normally closing the outlet orifice; a spider superposed upon the receptacle provided with means for securing the same to the closure-ring and with a central crown-toothed ratchet-wheel; means 25 for limiting the rotative movement of the spider upon the axis of the receptacle; a crown-toothed lift-ratchet-wheel coacting with the central crown-toothed ratchet-wheel of the spider; and means for partially 30 rotating the lift ratchet-wheel so as to lift the spider and closure-ring upon the tripping actuation of the thermo-trip and consequent rotation of the receptacle.

30. In a device of the class described, a receptacle adapted to contain a fire extinguishing fluidal material and to be revolvably carried by a suitable support; means for rotating the receptacle; a thermo-trip normally locking the receptacle against rotation; an outlet orifice in the annular wall 40 of the receptacle; closure means normally closing the outlet orifice; a trip-lever stop; and a resilient spring trip-lever adapted by its contact with the stop, upon the initial rotative movement of the receptacle, to throw the outlet closure means into the open position, and to be thereafter by its own resiliency thrown out of contact with the stop.

31. In a device of the class described, a receptacle adapted to contain a fire-extinguishing fluidal material having an annular peripheral wall provided with an outlet orifice in the form of a slit in such annular wall adjacent to the base of the receptacle; an 55 inner annular deflecting wall within the receptacle; and means for forcing the air down thru the space between the inner and outer annular peripheral wall and out thru the outlet orifice.

32. In a device of the class described, a receptacle adapted to contain a fire extinguishing fluidal material; means for pendulously supporting the receptacle with the axial pendulous line thereof in a substantially horizontal position; and a thermo-trip

normally holding the receptacle against pendulous movement upon the thermo-actuation of which thermo-trip the receptacle will be gravitationally vibrated upon its pendulous support.

33. In a device of the class described, a receptacle adapted to contain a fire extinguishing fluidal material; means for pendulously supporting the receptacle with the axial pendulous line thereof in a substantially horizontal position; means for rotating the receptacle; and a thermo-trip normally holding the receptacle against pendulous and rotative movement, upon the thermo-actuation of which thermo-trip the receptacle will be rotated and gravitationally vibrated upon its pendulous support.

34. In a device of the class described, a receptacle adapted to contain a fire-extinguishing fluidal material; a main support pendulously supporting the receptacle; a thermo-trip; and a secondary trip-cable secured at one end to the thermo-trip; a support thru which the secondary trip-cable freely passes; a weight upon the free end 80 of the trip-cable; and a stop secured to the trip-cable.

35. In a device of the class described, a receptacle adapted to contain a fluent fluidal fire-extinguishing material; a support revolvably supporting the receptacle; upon a pivot-pin motor-spring shaft pivotally supported by the support; a motor-spring secured at one end to the pivot-pin motor-spring shaft; means for connecting the other and free-working actuating end of the motor-spring with the receptacle by a releasable connection, automatically releasing such end of the motor-spring when the same reaches the limit of its receptacle actuating working throw; a ratchet-plate secured to the pivot-pin motor-spring shaft; means for locking the ratchet-plate against retroactive movement by the pressure of the motor-spring, automatically releasable upon the motor-spring reaching the limit of its receptacle actuating working throw; a thermo-trip normally locking the receptacle and motor-spring against movement; and a pawl-plate, 100 adapted to be removably secured to the support, adapted to coat with the ratchet-plate so as to successively and step-by-step lock such ratchet-plate against retroactive motion by the motor-spring, during the process of rewinding.

36. In a device of the class described, a support; a receptacle adapted to contain a fire-extinguishing fluidal material, and to peripherally expel the same therefrom when rotated revolvably carried by the support; means for positively rotating the receptacle; a thermo-trip normally locking the receptacle against rotation; and a substantially spiral deflecting vane within the receptacle, adapted to deflect and centrifugally direct the fire- 125

extinguishing fluidal material out of the receptacle, upon the actuation of the thermo-trip and consequent rotation of the receptacle.

5 37. In a device of the class described, a support; a receptacle, adapted to contain a fire extinguishing fluidal material, having a peripheral wall provided with an outlet orifice adjacent to the base; a closure normally closing the outlet orifice; a substantially spiral deflecting vane within the receptacle, adapted to deflect and centrifugally direct the fire-extinguishing fluidal material out of the receptacle upon rotation of the receptacle; means for positively rotating the receptacle; a thermo-trip; normally locking the receptacle and means for moving the outlet closure into the open position upon the actuation of the thermo-trip and consequent rotation of the receptacle.

10 38. In a device of the class described, a receptacle adapted to contain a fire-extinguishing fluidal material; means for giving fluidal expelling motion to the receptacle; and a thermo-trip normally locking the receptacle against movement comprising a main-plate removably secured in position, a rocking trip-lever secured to the main-plate by a suitable fusible-solder connection; and means for supporting the receptacle secured to the trip lever.

15 39. In a device of the class described, a receptacle adapted to contain a fire-extinguishing fluidal material; means for giving fluidal expelling motion to the receptacle; a thermo-trip normally locking the receptacle against movement, comprising a rocking trip-lever secured in locking position by a suitable fusible solder connection; and a supporting cable permanently secured at the end to the trip lever, and which is also releasably secured thereto at the bight of a loop formed therein by a suitable fusible solder connection.

20 40. In a device of the class described, a receptacle adapted to contain a fire extinguishing fluidal material; means for giving a rotative fluidal expelling motion to the receptacle; a thermo-trip normally locking the receptacle against rotative movement comprising a rocking trip-lever secured in lock-

ing position by a suitable fusible solder connection; and a support permanently secured to the trip-lever and also secured releasably thereto by a suitable fusible solder connection.

25 41. A device of the class described comprising a receptacle adapted to contain a fluidal fire-extinguishing material in the form of anhydrous fine powder; having an outlet orifice or orifices, located in the peripheral wall adjacent to the base end of the receptacle; closure means normally closing the outlet or outlets; a gyroscopic-frame pivotally revolvably supporting the receptacle therein; a normally tensioned coiled motor-spring releasably in actuating connection at one end with the receptacle adapted to put the receptacle into rotation, and to be automatically released from the receptacle when the limit of its throw is reached; a thermo-trip normally locking the receptacle and coiled motor-spring against movement; outlet closure mechanism normally closing the outlet or outlets; mechanism for moving such outlet closure mechanism into the outlet opening position upon the rotation of the receptacle; a main support secured to the upper non-base portion of the gyroscopic-frame, for pendulously gravitationally vibrating the frame and receptacle when thermally released; and an auxiliary support secured to the other end and base portion of the gyroscopic-frame in such manner as to be released from the gyroscopic-frame upon the actuation of the thermo-trip, whereby the device will be pendulously vibrated upon the main-support.

30 42. A fire-extinguisher comprising, a fluid container, means rotatably supporting said container, means for imparting a rotative movement to said container and adapted to automatically release from the container to allow it to spin following the initial impetus, means for effecting an opening in the container to discharge the fluid laterally, and a fusible member holding said container from rotation.

Signed at the city, county and State of New York, this 21st day of July, 1919.

CLARENCE LADD-DAVIS.
